CLAIM

The ornamental design for a mobile digital video camera, as shown.

DESCRIPTION

This design patent application is related to U.S. Design patent application Ser. No. 29/625,913, filed concurrently with this design patent application.

FIG. 1 is a front perspective view of a mobile digital video camera showing our new design;

FIG. 2 is a rear perspective view of the mobile digital video of FIG. 1;

FIG. 3 is a front elevational view of the mobile digital video of FIG. 1;

FIG. 4 is a rear elevational view of the mobile digital video of FIG. 1;

FIG. 5 is a left side elevational view of the mobile digital video of FIG. 1;

FIG. 6 is a right side elevational view of the mobile digital video of FIG. 1;

FIG. 7 is a top plan view of the mobile digital video of FIG. 1; and,

FIG. 8 is a bottom plan view of the mobile digital video of FIG. 1.
